UNITED STATES PATENT OFFICE.

HIRAM BRUCE TROUT, OF MATTOON, ILLINOIS.

VENTILATING WINDOW FOR PASSENGER CARS AND THE LIKE.

Application filed February 18, 1922. Serial No. 537,435.

To all whom it may concern:

Be it known that I, HIRAM BRUCE TROUT, a citizen of the United States, residing at Mattoon, in the county of Coles and State of Illinois, have invented certain new and useful Improvements in Ventilating Windows for Passenger Cars and the like; and I do hereby declare the following to be a full, clear, and exact description of the invention, such as will enable others skilled in the art to which it appertains to make and use the same.

This invention relates to improvements in ventilating apparatus, and more particularly to such as are especially adapted for use on vehicles, such as railway cars and the like.

The object in view is the facilitating of the admission or circulation of air under conditions assuring both the effective control of the quantity of air circulated and the physical condition of the air regarding freedom from dust, cinders, and other foreign substances.

A further object in view is the arrangement of the invention in such form as to be applicable to railway cars already in use as well as to new ones.

Another object in view is the provision of means for easily and readily varying the air intake according to the direction of travel.

With these and further objects in view as will in part hereinafter become apparent and in part be stated, the invention comprises certain novel constructions, combinations and arrangements of parts as subsequently specified and claimed.

In the accompanying drawings,—

Figure 1 is a view in side elevation of a fragment of a railway car equipped with an embodiment of the present invention and viewed from the inside of the car.

Figure 2 is a vertical section therethrough taken on the plane indicated by line 2—2 of Figure 1, parts being seen in elevation and the car seat being omitted.

Figure 3 is a perspective view of the ventilating apparatus detached.

Figure 4 is a vertical section taken on the plane indicated by line 4—4 of Figure 1.

Figure 5 is a horizontal section taken on the planes indicated by line 5—5 of Figure 4 and looking downward, the parts being in the position shown in Figures 3 and 4.

Figure 6 is a similar section of the same with the window shown closed.

Figure 7 is an enlarged, detail, fragmen-

tary section of a corner portion of the parts as seen in Figure 6.

Figure 8 is an enlarged, detail, fragmentary, vertical section taken on the plane indicated by line 8—8 of Figure 5.

Referring to the drawings by numerals, 1 indicates the side wall of a railway coach or other vehicle having the usual intramural space 2 above the window opening 3, and having a framing 4 surrounding the space 2 and opening 3, and provided with vertical grooves or other appropriate guides 5 for receiving the beads or other co-operating guides 6, 6, on the window sash 7. The sash 7 is rectangular, or otherwise shaped, to conform to and is slightly larger than the window opening 3, and is adapted to slide up into and down out of the space 2 from and to a position closing the window opening 3. The sash 7 is provided with an eye, or other appropriate anchoring means, 8, to which is connected a coiled spring or other suitable counter-balance 9, anchored at its upper end to the frame 4 for facilitating movement of the frame 7 upward to enable the passage of bedding or hose, or the permitting of a passenger to move through the window opening in the event of a wreck without the necessity for breaking the glass of the window hereinafter referred to. A handle 10 facilitates manual manipulation of the sash 7.

A glass-carrying frame 11 is arranged to move within the sash 7, and is proportioned vertically to fit snugly against the horizontal plates of sash 7, but is of sufficiently less width to provide spaces 12, 12, between the vertical plates of the sash 7 and the side walls of the frame 11, whereby the frame 11 is free to rock to and from a skewed or angular position, such as shown in Figures 3, 4 and 5. The frame 11 is a boxing, each plate of which boxing is equal in width approximately to the width of the adjacent plate of sash 7, and the side walls or plates of frame 11 are each made up of vertical strips connected by a screen, or other appropriate filter, 13. To the outer edge of the boxing, constituting the frame 11, there is fixed the molding 14, which is preferably of the hollow type, usually formed of metal, and arranged to carry the panes of glass 15, 15, there being two panes for the added protection afforded by the dual glass as now customarily employed in railway car construction. A cushioning pad of rubber, felt,

or other appropriate material, 16, is arranged between the panes 15 for insuring their effective retention in the molding 14.

The inner edge portions of the upper and lower horizontal walls of the frame 11 are cut-away, at 17, and rod springs 18, 18, functioning similarly to leaf springs, are arranged to lie principally within the area provided by the cut-away portions 17.

10 Projecting downwardly from the inner face of the upper plate of sash 7, and upwardly from the lower plate thereof across the space formed by the cut-away portions 17, are lugs 19, 19 carried by the sash 7.

15 Each rod 18 is bowed, as clearly seen in Figures 5 and 6, and has the central portion of the bow arranged beyond the respective lug 19, the end portions of each rod 18 being slidably extended into sockets

20 formed in the respective horizontal walls of frame 11, and the rods 18 being tensioned, when being assembled, so as to be under tension when in the position seen in Figure 6. Thus the frame 11, when free

25 to do so, seats itself naturally in its inward position, as seen in Figure 6, and remains in that position until otherwise moved. To prevent friction and noise, the outer edge of the sash 7 is preferably lined with a cushion 21 against which the inner face of molding 14 rests under the tension of spring 18.

30 Approximately midway in the length of the inner edge portion of each of the vertical walls of frame 11 there is provided a longitudinal notch 22 in which lies an operating arm 23, fixed to a rock shaft 24 journaled in the sash 7, and extending through and also journaled in a housing 25 hereinafter described. To the projecting inner end of

40 each shaft 24 is connected an operating crank 26 for facilitating manual manipulation of the frame 11, it being apparent that when either of the shafts 24 is moved angularly by the action of the respective crank 26, the

45 respective arm 23 will be swung vertically to the position seen at the right-hand side of Figure 5, whereby the arm 23 engaging the frame 11 in notch 22 moves the frame to the outer position seen in Figure 5. This

50 angular or tilted position is made possible of attainment by the frame 11 by virtue of its loose fit incident to the spaces 12, the frame moving out pivotally on the line of contact of the molding 14 with the vertical edge of sash 7 most remote from the particular shaft 24 and arm 23 being manipulated. Thus the opening covered by the

55 respective screen 13 is exposed for admitting air to the interior of the car. It will be obvious, of course, that the frame 11 will be re-seated by the action of springs 18 as soon as the respective arm 23 is returned to its lowered position, and it will also be apparent that, when desired, both of the arms

60 65 23 may be swung to their horizontal posi-

tion at the same time, and the whole frame 11 will thus be moved outward against the action of springs 18; whereby the side openings of both of the vertical sides of the frame 11 will be exposed. Thus the edge 70 opening of frame 13 at either edge may be exposed, according to the direction of travel of the car for freely admitting air, and the frame may be adjusted easily and quickly for reversing its relation to the balance of the structure so as to expose the other opening when the car is caused to move in the opposite direction, this being accomplished by the manipulation of the operating levers 26.

80 To prevent the collection of cinders and other foreign substances on the upper surface of the frame 11, when extended, a hood 27 is fixed to the wall 1 and outstands therefrom a distance sufficient to enclose and 85 cover the frame 11 in any of its positions.

If the shafts 24 were adequately journaled in the sash 7, or otherwise suitably rotatably connected therewith, the parts would function as described without the presence of 90 the housing 25, but there would be opportunity for leakage through one or the other of the openings 12, and, therefore, I provide a framelike housing 25 which extends about the inner edge of the sash 7 and is 95 fixed thereto. The housing outstands from the wall of the sash and is formed at an abrupt angle to extend about the frame 11 so as to completely conceal the same from 100 observation from within the car, while leaving the frame free to move in the space between the housing 25 and the sash 7. Thus, while guarding effectively against leakage of dust, or other foreign substance, the frame 11 is freely and easily manipulated either 105 by a passenger or an official by the operation of the levers 26, and the parts at the same time are given the finished appearance of the ordinary window. It will also be observed that when one of the levers 26 is 110 operated, it is moved to the position indicated in Figure 5, wherein the arm 23 is above the line of the axis of movement, having moved from the pendant position, as seen in Figure 4. The pressure of springs 18, tending to 115 restore frame 11, will cause the arm 23 to be pressed in its raised position against the terminus of the recess 22, whereby the frame 11 is locked in its adjusted position and will remain there until released by the 120 manual lowering of the respective lever 26.

What is claimed is:—

1. In a ventilator, the combination, with a sash, of a frame movable relative to the sash and having side openings adapted to 125 be alternatively exposed by such relative movement, and means for locking the frame with one of the side openings exposed.

2. In a ventilator, the combination, with a sash, of a frame movable therein and 130

- laterally beyond the sash upon either of its edge contacts with the sash as a line of pivot, means stressing the frame inward with respect to the sash, and means for locking the frame in an outwardly pivoted position, the frame being formed with openings located along its side portions for being alternatively exposed by alternative pivotal action of the frame.
- 10 3. In a ventilator, the combination, with a sash, of a frame movable therein and laterally beyond the sash upon either of its edge contacts with the sash as a line of pivot, means stressing the frame inward with respect to the sash, means for locking the frame in an outwardly pivoted position, the frame being formed with openings located along its side portions for being alternatively exposed by alternative pivotal action of the frame, and means for locking the frame with either of its side openings exposed.
- 15 4. In a ventilator, the combination, with a sash, of a frame movable therein and laterally beyond the sash upon either of its edge contacts with the sash as a line of pivot, means stressing the frame inward with respect to the sash, means for locking the frame in an outwardly pivoted position, the frame being formed with openings located along its side portions for being alternatively exposed by alternative pivotal action of the frame, and levers for shifting the frame pivotally for exposing either of its side openings.
- 20 5. In a ventilator, the combination, with a sash, of a frame movable therein and laterally beyond the sash upon either of its edge contacts with the sash as a line of pivot, means stressing the frame inward with respect to the sash, means for locking the frame in an outwardly pivoted position, the frame being formed with openings located along its side portions for being alternatively exposed by alternative pivotal action of the frame, the sash being shaped and proportioned for being moved into the intra mural space.
- 25 6. In a ventilator, the combination, with a sash, of a frame movable therein and laterally beyond the sash upon either of its edge contacts with the sash as a line of pivot, means stressing the frame inward with respect to the sash, means for locking the frame in an outwardly pivoted position, the frame being formed with openings located along its side portions for being alternatively exposed by alternative pivotal action of the frame, a shaft rotatably sustained at each vertical side of the sash, an operating arm for each shaft, and an operating lever for each shaft, each of the operating arms being in line with a portion of the frame for shifting the frame when the respective lever is manipulated.
- 30 7. In a ventilating structure, the combination, with a wall having an intra mural space, and a sash mounted in the wall, of a frame movable therein and laterally beyond the sash upon either of its edge contacting with the sash as a line of pivot, means stressing the frame inward with respect to the sash, and means for locking the frame in an outwardly pivoted position, the frame being formed with openings located along its side portions for being alternatively exposed by alternative pivotal action of the frame, the sash being shaped and proportioned for being moved into the intra mural space.
- 35 8. In a railway car structure, the combination, with the wall of a car having a window opening and an intra mural space, and a sash slidably mounted for closing the opening and sliding therefrom into the intra mural opening, of a frame movable in the sash and laterally beyond the same upon either of its edge contacts with the sash as a line of pivot, means stressing the frame inward with respect to the sash, and means for locking the frame in an outwardly pivoted position, the frame being formed with openings located along its side portions for being alternatively exposed with alternative pivotal action of the frame, the frame being movable by the sash into the intra mural space with the sash when in its inner position.
- 40 9. In a railway car ventilator, the combination, with the wall of a car having a window opening and a sash mounted therein, of a frame movable in the sash and laterally beyond the same upon either of its edge contacts with the sash as a line of pivot, means stressing the frame inward with respect to the sash, means for locking the frame in an outwardly pivoted position, the frame being formed with openings located along its side portions for being alternatively exposed by alternative pivotal action of the frame, the sash being shaped and proportioned for being moved into the intra mural space with the sash when in its inner position.
- 45 10. In a ventilator, the combination, with a sash, of a frame movable therein and laterally beyond the sash upon either of its edge contacts with the sash as a line of pivot, means stressing the frame inward with respect to the sash, means for locking the frame in an outwardly pivoted position, the frame being formed with openings located along its side portions for being alternatively exposed by alternative pivotal action of the frame, and a hood outstanding from the outer face of the car wall for overhanging and enclosing the upper portion of the frame when in its outermost position.
- 50 11. In a ventilator, the combination, with a sash, of a frame movable therein and laterally beyond the sash upon either of its edge contacts with the sash as a line of pivot, means stressing the frame inward with respect to the sash, means for locking the frame in an outwardly pivoted position, the frame being formed with openings located along its side portions for being alternatively exposed by alternative pivotal action of the frame, and a hood outstanding from the outer face of the car wall for overhanging and enclosing the upper portion of the frame when in its outermost position.
- 55 12. In a ventilator, the combination, with a sash, of a frame movable therein and laterally beyond the sash upon either of its edge contacts with the sash as a line of pivot, means stressing the frame inward with respect to the sash, means for locking the frame in an outwardly pivoted position, the frame being formed with openings located along its side portions for being alternatively exposed by alternative pivotal action of the frame, and a hood outstanding from the outer face of the car wall for overhanging and enclosing the upper portion of the frame when in its outermost position.
- 60 13. In a ventilator, the combination, with a sash, of a frame movable therein and laterally beyond the sash upon either of its edge contacts with the sash as a line of pivot, means stressing the frame inward with respect to the sash, means for locking the frame in an outwardly pivoted position, the frame being formed with openings located along its side portions for being alternatively exposed by alternative pivotal action of the frame, and a hood outstanding from the outer face of the car wall for overhanging and enclosing the upper portion of the frame when in its outermost position.
- 65 14. In a ventilator, the combination, with a sash, of a frame movable therein and laterally beyond the sash upon either of its edge contacts with the sash as a line of pivot, means stressing the frame inward with respect to the sash, means for locking the frame in an outwardly pivoted position, the frame being formed with openings located along its side portions for being alternatively exposed by alternative pivotal action of the frame, and a hood outstanding from the outer face of the car wall for overhanging and enclosing the upper portion of the frame when in its outermost position.

the frame in an outwardly pivoted position, the frame being formed with openings located along its side portions for being alternatively exposed by alternative pivotal action of the frame, and a housing connected to the inner edge of the sash and shaped to extend within the frame and close the spaces between the frame and sash.

11. In a ventilator, the combination, with a sash, of a frame movably carried thereby and formed with openings for ventilating purposes, means for moving the frame laterally with respect to the sash for exposing the ventilating openings, and an arched spring engaging the sash and the frame and stressed for resisting such movement of the frame.

12. In a ventilator, the combination, with

a sash, of a frame carried thereby and movable relative thereto and having ventilating openings, means for moving the frame for exposing the ventilating openings, the frame being formed with spaced sockets and a bowed spring connected intermediate its ends to the sash and having its end portions extending into the sockets, the spring being tensioned for resisting movement of the frame toward any position exposing any of the ventilating openings.

In testimony wherof I affix my signature in presence of two witnesses.

HIRAM BRUCE TROUT.
